MOUNTING FOR LOOP AERIALS.

Application filed December 8, 1924. Serial No. 754,475.

This invention relates to antenna for radio reception and more particularly to an improved mounting for loop aerials and the like.

- 5 The directional characteristics of a loop antenna or aerial are well known in the art. These characteristics make it desirable to provide antennæs of this sort with a mounting which will permit turning of the aerial 10 to the desired position with respect to the station from which it is desired to receive, to take advantage of said characteristics, in tuning the receiving circuit to the waves radiating from the sending station.
- 15 Good contact and a connection between the aerial and receiving or other circuit in which the functioning of the contacts and associated leads will not be impaired by turning of the aerial into different positions is 20 also highly desirable.

According to my invention I provide a generally improved, simplified and inexpensive aerial mounting which will permit turning the aerial as desired with ease and convenience and which will, at the same time, provide circuit connections from the aerial to the receiving circuit, which will not be impaired by the adjustability provided nor by the turning of the aerial but will maintain 25 a proper connection and good contact at all times.

To make the structure as simple and inexpensive as possible, consistent with good operation, I have arranged to use a minimum 30 number of standard parts. I take what amounts to a regular or standard jack and a cooperating plug and by giving the jack relatively stationary support and mounting the aerial carrying post or frame on the plug so 35 that the plug is rotatable therewith, convenient turning of the aerial is permitted and at the same time good connection and contact is provided at all times to the jack circuit.

The twisting and stressing of slackened connections between fixed terminals and the 40 taps of a rotatably mounted aerial are eliminated. The mounting is firm and sturdy and the relatively stationary jack contact is, as 45 already pointed out, what amounts to a jack 50 so that the panel and plate borings and mountings for this and the jacks employed may be standardized. I also provide for preventing the showing of any tilting of the antenna and novel cord tip sleeves or jack

terminal means adapted to be inserted or 55 passed through a minimum sized opening in the panel, mounting base or plate.

To acquaint those skilled in the art with the structure and manner of practicing my invention, I shall now describe a particular 60 embodiment of the same in connection with the accompanying drawings, in which:

Figure 1 is a front elevational view of a 65 loop aerial mounted according to my invention;

Fig. 2 is a detail elevational view of the mounting;

Fig. 3 is a vertical section taken on line 3—3 of Fig. 2;

Fig. 4 is an elevational view of a modification looking in a direction at right angles to the direction at which Fig. 2 is viewed;

Fig. 5 is a fragmentary detail section vertically through the axis of the relatively stationary jack contact mounting of Fig. 4, 70 showing the plug in elevation; and

Fig. 6 is an end view of the jack from below showing the terminal or cord tip sleeves of the jack.

Referring first to Figures 1 and 2, 5 designates a panel or plate which may be the wooden top wall of the cabinet for the receiving set or any other suitable panel, shelf or plate. The panel 5 has an opening 6 which may be of generally circular formation 75 and the jack is inserted through this opening in assembly as will be hereinafter pointed out.

The mounting or flush plate 7 is attached by screws 8 to the top of the panel 5 over the opening 6 and has an opening 9 concentric with the opening 6. A sleeve or thimble 10 having a head 11 overlying the plate 7 passes down through the opening 9, and below the plate 7 threads into the thimble leg 90 or lateral ear 12 of a jack frame or bracket 13. A collar 14, surrounding the thimble 10 and interposed between the plate 7 and ear 12, spaces the ear 12 from the plate 7 to properly position the hump 15 of the tip contact spring 95 for proper co-operation with the hill and valley in the plug tip 17 when the plug is inserted into the jack.

The jack frame has a base 18 and the contact spring 16 is mounted with a ground contact spring 19 upon said base, the spring contacts 16 and 19 being insulated from each other by strips 20 of fibre or other suitable 100

insulating material interposed therebetween. Screws 21, passing through apertures in the contact springs 16 and 19 and strips of insulation 20 and threaded into the base 18, firmly 5 secure the contact springs and strips of insulation to said base, said screws 21 being surrounded by insulating bushings 22 which insulate them from the contact springs. The contact spring 16 is, as already pointed out, the tip spring for contact with the plug tip and the spring contact 19 is the ground contact and it contacts directly with the frame 13 and is connected through said frame with the thimble or sleeve 10.

15 The lower ends of each of the springs 16 and 19 has a longitudinally extending portion or depending ear 23. Contact sleeves 24 are slotted diagonally at one end to fit over the ears or longitudinally extending portions 23 and one sleeve 24 is fit over each ear and soldered in place thereon. It should be noted that the sleeves 24 are mounted upon opposite sides of the respective spring contacts, the sleeve mounted upon the contact spring 16 being shown offset laterally to the right in Fig. 2, and the other sleeve offset laterally to the left. This staggers the sleeves with respect to each other and in effect disposes them diagonally across the lower ends of the 30 contact springs and insulating strips mounted on the base 18, making the terminal sockets 24 compact and permitting insertion of them and the entire jack through an opening 6 of minimum diameter.

35 The slots for receiving the ears 23 extend diagonally through the generally circular ends of the sleeves 24 and spaced from said ends each sleeve 24 has a generally rectangular flat surface 25, milled or otherwise formed therein. The sleeves 24 have eccentric sockets for receiving the conductors 26 for connecting the jack in circuit with the receiving set. Screws 27, threaded laterally into the socketed ends of the sleeves 24 through the 40 flat surfaces 25, are adapted for clamping the conductors in the sockets of the sleeves 24. The flat surfaces 25 are by this disposition, disposed diagonally across the lower end of the generally rectangular jack spring and insulating strip unit as shown in Fig. 6 and the screws 27 are disposed diagonally at right angles to said surfaces for convenient access and without appreciable projection from the 45 sides of said unit when extended. This lends itself to the desired compactness for insertion through an opening 6 of minimum size.

50 The plug comprises an upper body member 30 and a lower body member 31 underlying said first body member and both being of brass, or other suitable conducting material, and insulated from each other by a fibre or other suitable insulating washer 32.

55 The contact post of the plug comprises a sleeve contact 33 passing through and secured in the sleeve body 31 in contact therewith and

a needle 34 extending concentrically through the sleeve 33 and insulated therefrom by an intervening sleeve 35 of fibre or other suitable insulation. The tip 17 is threaded upon and in contact with the lower end of the 70 needle 34 and is insulated from the sleeve 33 by an insulating washer 35. The tip 17 at the lower end of the needle 34 may be touched with solder to secure it firmly in place. The upper end of the needle 33 is threaded into 75 the needle body 30 in contact therewith and binds the parts firmly together. The upper end of the needle may be headed or riveted over, or touched with solder if desired.

80 The upper part of the body member 31 is reduced to substantially the diameter of the body member 30, forming a radial flange at its lower end and fitting over the body member 30, and the reduced upper part of the body member 31 with its lower open end adapted for engagement with this radial flange, is a sleeve 38, which may be formed of fibre tubing, or other suitable insulating material. The upper end of the sleeve 38 has an insulating washer 39 suitably secured therein and this head has an axial opening for receiving the lower end of the upright aerial carrying post 40, which is adapted to extend down concentrically through the sleeve 38 and to seat at its lower end in a socket 42 in the upper surface of the body member 30. The post 40 may have a pressed fit in the head 39 or it may be squared or of non-circular formation for co-operation with a similarly formed opening in head 39 or similarly formed socket in body member 30, or the antenna post and plug may be otherwise connected for rotation together.

85 A pair of screws 45 pass laterally through the sleeve 38 and by threading one of said screws into each of the body members 30 and 31, they perform the dual function of securing the sleeve in place upon said body members, and providing plug terminals to which 90 the leads or taps 46 from the aerial loop 48 are adapted for connection. I have shown each lead or tap 46 as provided with a terminal 49, and to bind said terminals 49 firmly and in any desired position upon the screws 45 without adjusting said screws and independent of the heads thereof, I thread upon each screw a pair of binding nuts 52 which may be independently adjusted along the 95 screws 45 and drawn up to bind the terminals 49 between them, and when so drawn up, form lock nuts, one for the other.

100 In assembling, the mounting plate 7 and jack frame are secured together in spaced relation by the thimble 10 and the entire jack with the contacts on its base 18 is inserted through the opening 6 in the mounting board or panel 5 and the plate 7 is attached to the 105 top of said board or panel. When the plug is inserted, the hexagonal upper end of thimble 10 forms a seat for the lower flanged end 110

of body 31 and by providing a clearance between the mounting plate and said body, keeps any tilting of the plug or aerial from showing.

5 In use, the plug when inserted in the jack is rotatably mounted therein, and the spring contact 16, by its wiping contact with the plug tip 17, permits turning of the aerial 48 as desired for directional purposes and maintains good contact at all times between the aerial and jack circuits. The connecting of the aerial leads or taps to the terminals 45, and the leading of one or both of the connections down through the rotatable aerial 15 mounting post, permits turning of the aerial as desired without the necessity of slackening the leads and without the possibility of twisting, stressing or winding said leads about the post of the aerial.

20 In Fig. 4 I show an additional spring arm 60 mounted with the spring arm 16 and strips 20 upon the base 18 of the jack frame. When the plug post or tip is inserted, this additional spring 60, which need serve no current carrying function, has a hump 62 at its upper end which co-operates with the tip 17 of the plug diametrically opposite the hump 15, thereby providing a balanced spring arrangement for holding the plug tip firmly 25 in place and in good contact with the contact spring without any tilting or objectionable inclination of the plug.

In Figs. 4 and 5 I have also shown the thimble or sleeve 10' as rigidly fixed in the mounting plate 7', its upper end being riveted or headed over at 65, flush with the upper surface of the plate 7', said sleeve 10' being externally threaded, as before, for threaded engagement with a tapped opening in the lateral leg or ear 12' of the jack frame, a suitable spacing collar 14' being interposed between the ear 12' and the plate 7' to position the contact springs of the jack for proper co-operation with the plug tip. 45 Where interchangeability of the spacing collars is not desirable, the spacing shoulders may obviously be formed integral with the thimble or sleeve 10'. In this case, upon insertion of the plug, the lower flanged end 50 of the body member 31 co-operates directly with the upper surface of the plate 7', giving a larger area of co-operation than where a headed end of the thimble is interposed therebetween, and because of said larger area 55 of cooperation, a firmer seating and this with the balanced springs cooperating with the plug tip makes tilting or undesirable inclinations of the plug less likely.

I do not intend to be limited to the precise

details shown or described. The leading of 60 the aerial leads down the rotatably mounted post is an important aspect of the invention, and in this connection it is to be pointed out that the extending of one lead only down such a post is of course contemplated within 65 the scope of my invention. A minimum number of standard parts are employed and ease and convenience of turning of the loop aerial or antenna for directional purposes, with good contact at all times, is secured. 70

I claim:—

1. In combination, an aerial having leads extending therefrom, a pair of body members insulated from each other, a plug post comprising a sleeve contact connected in contact with one of said body members, a needle contact passing through and insulated from said sleeve contact and threaded into the other body member, a sleeve of insulation mounted upon said body members, and adapted to receive an aerial post, and a pair of screws passing laterally through said sleeve and threaded one into each of said body members, said screws forming terminals for the aerial leads. 85

2. In combination, an aerial having leads extending therefrom, a pair of body members insulated from each other, a plug post comprising a sleeve contact connected in contact with one of said body members, a needle contact passing through and insulated from said sleeve contact and threaded into the other body member, a sleeve of insulation mounted upon said body members and adapted to receive an aerial post, a pair of screws passing laterally through said sleeve and threaded one into each of said body members, said screws forming terminals for the aerial leads and a jack for receiving the plug, the aerial being connected in circuit with 100 said jack through said needle and sleeve contacts. 90

3. In combination, an aerial having leads extending therefrom, a pair of body members insulated from each other, a plug comprising two exposed insulated contacting portions, said portions being connected to the respective body members, a sleeve of insulation mounted upon said body members and adapted to receive an aerial post, and a 105 pair of screws passing laterally through said sleeve and threaded one into each of said body members, said screws forming terminals for the aerial leads. 110

In witness whereof, I hereunto subscribe 115 my name this 5th day of December, 1924.

RILEY M. DIENER.
